UNITED STATES PATENT OFFICE.

SPENCER C. CARY, OF BROOKLYN, NEW YORK, ASSIGNOR TO CARY MANUFACTURING CO., OF BROOKLYN, NEW YORK, A CORPORATION OF NEW YORK.

SHIPPING PACKAGE.

Application filed May 6, 1919. Serial No. 295,245.

This invention pertains to shipping packages, the salient feature of which consists of metallic binders applied under tension and positioned within the end portions of 5 said package for the performance of several functions, chief among which is that of compressing the slats or boards of the package so as to add materially to the strength and stability of the resulting structure.

10 Heretofore it has been customary to apply flat metallic strapping to boxes or cases at the ends thereof, and to attach the same by nailing the strapping in position, said strapping being free or substantially free 15 from tension and operating by the inherent strength of the metal to increase the stability of the package. It has been customary, also, to apply wire binding material to the ends of the package, but such 20 wire binders, although drawn more or less taut, have been insufficient as factors in compressing the material of the box or case, for the reason that such wire binders are applied to the ends of the box and they are 25 drawn only to an extent requisite for taking up the slack in the binding material without, however, compressing such material, as contemplated by my invention.

According to my invention it is preferred 30 to construct a box the top and bottom of which are somewhat less in width, say one-eighth of an inch or more on each side, than the total width of the box structure, and to apply a plurality of binders to the box 35 within the end members thereof, say two or three inches, or more, it being essential in my invention to draw or stretch the binders so tightly and into such intimate contact with the box that the sides of the box 40 structure are compressed and drawn inwardly by the binders, as a result of which the sides are deflected or bowed inwardly from their lines of attachment to the end members by the tension of the binders, and thus 45 the box sides intermediate the end members are positioned for the edges of said sides to be flush, or substantially so, with the edges of the top and bottom respectively, whereby the binders so tightly hold and retain all 50 parts of the box structure in such firm relation that the stability of said box structure is to a large extent not dependent upon the security ordinarily afforded by the nailing employed for the attachment of the sides to 55 the bottom and the top.

A shipping package embodying my invention is composed of solid or relatively thick end members, slats or boards the ends of which are desirably attached, as by nailing, to the end boards, it being desirable to use 60 a top and a bottom, the width of which is less than the total width of the resulting box structure, and two or more metal binders stretched around and drawn into tight contact with the boards, slats, or other material, 65 said binders being positioned back from the ends and being drawn so tightly as to compress the boards or slats. Each binder is joined, preferably by a seal operating to lock the ends of said binder and thus the 70 binders contribute to the stability of the package and the sealed connections of the binders afford added security against loss of the contents by theft.

In my package it is not required to nail 75 or otherwise attach the tops or bottoms to side boards or slats along the sides of the box structure, for the reason that the binders are applied intermediate the ends, and thus 80 said binders perform a double function, i. e., the sides are drawn inwardly from a straight line between the end members, and the binders act as stays in retaining the side walls against bulging outwardly under the weight 85 of the contents of the box. Furthermore, the top, bottom and sides of the box or case may be and preferably are composed of relatively thin material, such as boards or slats, whereof the top and bottom cannot be nailed 90 to the sides however such nailing may be desirable, but in this invention the occasion for nailing the tops and bottoms to the sides of the box is wholly obviated for the reason, among others, that the metal binders applied under tension so strengthen and stiffen the 95 several walls of the box structure that the desired stability is obtained.

Other functions and advantages of the invention will appear from the following detailed description taken in connection with the drawings, wherein—

Fig. 1 is a perspective view of one form of the shipping package showing binders at the middle and end portions of the box structure.

Fig. 2 is a perspective view of a preferred form of the box showing the deflection of the sides inwardly between the ends due to the compressing effect of the binders applied under tension.

Fig. 3 is a perspective view of a box partly broken away with one of my binders applied under tension and illustrating the compressing effect obtained by the tension of the binder upon each of the sides of the box structure.

The box or case shown in the drawings is composed of end members A B, slats or boards C forming the walls at the top, bottom and sides, and two or more metal binders D, E, F. The end members A B are composed usually of relatively thick and solid pieces of wood, to which the slats or boards C are fastened, usually by nailing the parts together at c. The nails are driven through the end portions of the slats and into the end members, no nails being driven through the slats on one side and into the slats on the adjacent side, as is customary, the effect of such side nailing when thin slats are used being to split or crack the boards and to displace one part of the board while leaving another part in a partially open or gaping relation to adjacent slats.

In the preferred form of the box structure shown in Fig. 2, the top and the bottom are each composed of one or more pieces, the width of said top or bottom being less than the total width of the box. The sides of the box structure are not flush with the edges of the top or bottom, there being spaces of appreciable width between the edges of the sides adjacent the edges of the top and bottom. After the sides, top and bottom are nailed to the ends, the binders are applied, drawn tight and sealed, said binders being positioned two or more inches from the ends of the box and said binders being drawn with such force as to compress the sides of the box structure, the effect of which as shown in Fig. 2 is to deflect each side inwardly from the lines of attachment to the ends and to substantially draw the edge portions of the sides into flush relation to the edges of the top and bottom, such flush relation of the sides to the top and bottom being intermediate the end members and such binding effect being due to the tension under which the binders are drawn into forcible contact with the walls of the box structure.

The binders D E are applied around the box not at the ends thereof nor are they nailed to the box, as is customary, but on the contrary, said binders D E are positioned within or adjacent the ends, say two or more inches from said ends, dependent upon the length of the box. It is essential that the binders be stretched or drawn tightly around the box and into contact with the material composing the same, whereby the slats or boards at the sides of the box structure are closed or drawn into flush relation to the top and bottom by the tension of the binders. For this purpose, it is desirable

that the binders be placed under tension by a suitable stretching mechanism, the same operating to place tension upon the binders less than the breaking point. It is apparent that the binders cannot be nailed or otherwise attached to the slats C for the reason that the latter are composed of relatively thin material in which the nails will not hold, and to retain the binder so placed under tension I employ means for locking the lapping end portions of said binder, to which end it is preferred to seal the lapping ends by the use of a seal member G. The lapping ends e are embraced by a seal member G, and the latter is subjected to pressure so as to interlock the lapping ends e and the seal member G, thus effectively locking the end portions of the binder under tensional strain. The described means enables me to dispense with the operation of nailing the binder to the package; it enables the binder to be locked under tension for compressing the slats or boards into firm relation; the seal adds to the security of the package so as to minimize loss of the contents by theft, and the binders under tension increase the stability of the package by the inherent strength of the metal and by such compression of the sides of the package at points intermediate the ends thereof.

My means for stiffening the walls of the package so increases the strength and stability thereof that the package may be desirably constructed of thinner boards or be composed of thinner and lighter material, thus enabling me to effect a desirable economy in the manufacture of the cases or boxes in large quantities.

Boxes of considerable length are rendered stable by binders applied under tension near or within the ends thereof, but should the contents of the package be so heavy as to displace or bulge the walls intermediate the ends or between the binders D E it may be desirable to use one or more additional binders as F between the first mentioned binders D E, see Fig. 1. The binder F is applied under tension, and its ends sealed and locked in the manner described.

As will be understood, each binder may consist of a length of flat metal strapping or it may be composed of wire, the metal used possessing sufficient tensile strength to withstand the strain of application under tension and of the weight and strain during shipment.

Having thus fully described the invention, what I claim as new, and desire to secure by Letters Patent is:

1. A shipping container comprising a pair of rectangular box ends, three box sides, secured to said ends, a fourth box side made of springy sheet material, applied upon said ends and cut away at its longitudinal edges,

so as to be adapted to be forced inwardly intermediate said ends between the adjacent edges of the adjacent sides, and tensional binding means applied upon said box under heavy pressure and maintaining said fourth side in its distorted position.

2. A shrinkage compensating reinforced shipping container, comprising a pair of rectangular box ends; side material connected to said ends to form box sides, a portion of said box sides being springy, and cut away at the edges to permit the region of the box intermediate the ends to be compressed into a cross sectional area less than at the ends; and tensional box binding means applied about said box intermediate the ends to so constrict the box intermediate the ends; whereby the reaction of the compressed side material against compression serves to maintain the tensional binding means taut under shrinkage of the box material or the like.

3. A shrinkage compensating reinforced shipping container comprising, in combination, a pair of box ends; box sides, secured to said ends, certain of said box sides being composed of springy wooden side material and cut away at the lateral edges to permit the same to pass inwardly between the adjacent edges of other box sides when the container is constricted intermediate its ends; and tensional binding means constricting said container intermediate its ends into an inner cross sectional area less than that at the box ends, whereby the binder loosening effect of wood-shrinkage is avoided.

4. A shrinkage compensating reinforced shipping container comprising, in combination, a pair of box ends; wooden box sides secured to said ends; a portion of said box sides being cut away at their longitudinal edges, to permit constriction of the box intermediate its ends into an inner cross sectional area less than that at the ends; and tensional binding means applied upon said box intermediate its ends to constrict the same into said smaller cross sectional inner area, whereby slippage of the binders off the ends of the boxes is prevented.

5. A shrinkage compensating shipping container having initial compressibility and an inherent limit of constriction, comprising box ends, springy side material applied thereabout, adjacent edges of said side material being relatively cut away and arranged so that, under constriction by a binder or the like intermediate the box ends, a springy box side may be distorted inwardly until relieved against further inward motion by an adjacent box side to produce a rigid corner edge, and a tensional binder distorting said box side toward said limit of box constriction, whereby constrict-

ing pressure may be applied to the box beyond the pressure effective to constrict the same, and shrinkage compensation effected by the reaction of the springy side to the initial distortion.

6. A shrinkage compensating reinforced shipping box, comprising a pair of box ends; springy side material, applied upon said ends to form box sides, the longitudinal edges of said box sides being relatively arranged with respect to each other to provide a predetermined corner edge configuration intermediate the ends of the box when the springy side material is compressed inwardly toward the center of the box, and tensional binding means applied to the box under substantial tension to constrict the circumference of the box intermediate its ends, and compress the springy side material into said corner edge configuration.

7. A reinforced shrinkage compensating shipping container comprising, in combination, box ends, springy side material applied on said box ends to form box sides, the longitudinal edges of certain of said sides being relatively cut away and located with respect to other box sides as to define, by coming into contact at the box corner edges equal limits of constriction, intermediate the box ends at a plurality of the box corner edges, when constricted by the application under tension of a tensional reinforcing binder applied intermediate the box ends.

8. A shrinkage compensating reinforced shipping package, comprising, in combination, a box, comprising a pair of box ends, springy side material, applied upon said ends to form box sides, the longitudinal edges of certain of said sides being relatively cut away and arranged with respect to each other, to automatically define limits of constriction of the box circumference intermediate the ends, tensional binding means applied about said box intermediate its ends to constrict said box toward said limits of constriction.

9. A shipping container comprising a box bottom and a pair of box sides, box ends to which said parts are applied, a wooden box top made of springy material applied upon said box ends, and having its upper face located, when undistorted, substantially above the tops of said box sides, the longitudinal edges of said box top being cut away sufficiently to permit the same to be distorted intermediate of the box ends, and tensional binding means applied about the box intermediate its ends and so distorting the box top.

In testimony whereof I have hereunto subscribed my name.

SPENCER C. CARY.
